(57) **CLAIM**

The ornamental design for a control device, as shown and described.

DESCRIPTION

FIG. 1 is a side view of a control device showing our new design;

FIG. 2 is an end view of the control device shown in FIG. 1; FIG. 3 is a top view of the control device shown in FIG. 1; FIG. 4 is a right perspective view of the control device shown in FIG. 1; and,

FIG. 5 is a left perspective view of the control device shown in FIG. 1.

The broken lines show transition points for curved features and form no part of the claimed design.
